(57) **CLAIM**

The ornamental design for a set of surfboard fins, as shown and described.

DESCRIPTION

FIG. 1 is a first isometric view of the set of surfboard fins of the present invention;

FIG. 2 is a second isometric view of the invention of FIG. 1;

FIG. 3 is a side view of the invention of FIG. 1 as seen from a bottom side of FIG. 6;

FIG. 4 is a side view of the invention of FIG. 1, as seen from the top side of FIG. 6;

FIG. 5 is a top plan view of the invention of FIG. 1;

FIG. 6 is a bottom plan view in elevation of the invention of FIG. 1;

FIG. 7 is a front view of the invention of FIG. 1, as seen from the right side of FIG. 4; and,

FIG. 8 is a back view of the invention of FIG. 1, as seen from the left side of FIG. 6.

The broken lines showing a surfboard are included for contextual purposes and form no part of the claimed design.
